APPARATUS FOR LIXIVIATING RAW
MATERIAL IN STAGESEgon Böhm, Vienna, Austria, assignor to Karl
Friedrich Wilhelm, Stralsund, GermanyApplication December 4, 1935, Serial No. 52,924
In Germany December 18, 1930

1 Claim. (Cl. 87-28)

The invention relates to an apparatus by which constituents of raw materials can be continuously dissolved out and the solvent is led through the material to be lixiviated for this purpose. (This 5 is a continuation in part of the divisional application Ser. No. 712,433, filed 21-2-1934, and accordingly certain parts of the subject matter of the later application will be found in the earlier application.)

10 In the known methods the raw materials are subjected to repeated treatment with the solvent in a closed container or the solvent is led through stationary containers containing the raw material, which are each closed and arranged in series, by means of pipe conduits. It has also already been proposed to move the raw material forwards in a chamber closed on all sides in containers having sieve bottoms and being open at the tops, while the solvent is allowed to flow freely 15 in the opposite direction through all the containers successively. It has already been proposed to move the raw material in the chamber not forwards but first downwards and then upwards, while the solvent is led through the material in 20 the downwardly moving containers in the same direction and through the material in the upwardly moving containers in the opposite direction.

25 In contradistinction thereto the present invention consists in this that the raw material is moved in horizontal annular containers, which are arranged centrally in a chamber, which is closed on all sides, at different heights about a common vertical axis. Each of these containers 30 consists of a rotatable sieve bottom and one side wall rigidly connected with this, while the other side wall which can preferably be heated is stationary. The rotatable sieve bottom moves very close to the stationary wall. This stationary wall 35 of each container is interrupted at one part and provided with a scraping device reaching into the interior of the container the sieve bottom and the other side wall, which conveys the material, moved with the rotatable part of the container 40 in the manner of a conveyor band, into the next lower container. From the container at the bottom of the chamber the material passes out through an opening in the wall of the chamber.

45 During the movement of the raw material by the containers, solvent is passed through all the containers successively by means of a pump from the bottom to the liquid distributor of the next higher container and from this distributor in free fall 50 into the container belonging thereto, so that

the fat content is increased continuously from the bottom to the top.

In the accompanying drawing an example of the invention is illustrated.

Fig. 1 is a vertical section along line I—I of Fig. 5 Fig. 2 and Fig. 2 is a horizontal section along line II—II of Fig. 1.

In the chamber *a*, which is closed on all sides, the circular containers *b*¹, *b*², and *b*³ are arranged centrally one above the other. The container *b*², 10 which lies between *b*¹ and *b*³, preferably has a smaller diameter than these in order that the material delivered from the container *b*¹ through its opening *l*¹ of the stationary side wall by means of the scraping device *h*¹ may be brought into 15 the container *b*². Each of the containers *b*¹, *b*² and *b*³ consists respectively of the sieve bottoms *c*¹, *c*², and *c*³, and the side walls *d*¹, *d*², and *d*³, rigidly connected therewith and of the stationary double side walls *e*¹, *e*², and *e*³, which can be 20 heated. The sieve bottoms of the containers with the connected side walls are rotatable. Below the containers *b*¹, *b*², and *b*³ are the flat stationary troughs *f*¹, *f*², and *f*³, in which the solvent flowing through the sieve bottoms *c*¹, *c*², and *c*³ 25 is caught up. Above the containers *b*¹, *b*², and *b*³ are respectively arranged the pipe conduits *g*¹, *g*², and *g*³ from which the solvent passes to the distributors *m*¹, *m*², and *m*³ respectively and from there into the containers *b*¹, *b*², and *b*³ respectively. 30 The solvent conduit *g*² is connected with the trough *f*³, the solvent conduit *g*¹ with the trough *f*². The solvent conduit *g*³ is supplied with the solvent from a reservoir and the solvent conduit *g*⁴, which leads away the solvent from the trough 35 *f*¹, which is most enriched with the substances dissolved out of the raw material, opens into a collector outside the chamber *a*. In the solvent conduits *g*¹ and *g*² pumps *p*¹ and *p*² are interposed 40 for delivering the solvent. The upper cover of the chamber *a* is penetrated by the filling hopper *t* through which the raw material to be lixiviated is brought into the container *b*¹; the lower end of the chamber *a* is penetrated by the outlet opening *k* through which this lixiviated raw material scraped off from the lowest container *b*³ is 45 delivered to the outside.

The containers *b*¹, *b*², and *b*³ are rotatable about the axis *n*, which is brought in rotation by the bevel gear system *o*. Of the container *b*¹ the sieve bottom *c*¹ and the outer wall *d*¹ are brought in rotation by the axis *n*, whilst the wall *e*¹ is stationary with the chamber *a*. Of the container *b*² the inner wall *d*² and the sieve bottom *c*² are 50 brought in rotation by the axis *n* and the outer 55

wall e^3 is stationary. Of the container b^3 the outer wall d^3 and the sieve bottom c^3 are brought in rotation by the axis n , whilst the inner wall e^3 is stationary. The containers are rotated with the sieve bottoms in order to convey the material against the scraping devices and along the same into the next lower containers. To conduct the solvent coming from the pipe conduits g^3 and passing through the trough f^3 into the pipe conduits g^2 pumps p^2 are arranged in the pipe conduits g^2 between the trough f^2 and the distributor m^2 . To conduct the solvent from the trough f^2 into the distributor m^1 pumps p^1 are arranged in the pipe conduits g^1 . The distributors m^1 , m^2 , and m^3 can be provided in any number above every container; Fig. 2 shows three distributors by way of example. The apparatus described by way of example is used in the following manner:

Raw material is brought into the container b^1 in a continuous stream through the filling hopper l . The sieve bottom c^1 and the side wall d^1 of the container b^1 are in rotation and carry the material coming from the filling hopper l with them until it reaches the scraping device h^1 and by this is caused to pass through the opening l^1 of the stationary side wall e^1 out of the container. The material falls on to the part immediately underneath the opening l^1 , i. e. the container b^2 , which also has its movable part rotating, in which the same procedure takes place until the material reaches the container b^3 and from this falls out through the outlet opening k . During the movement of the raw material in the containers b^1 , b^2 , and b^3 , solvent is brought over the raw material by means of the pipe conduits g^1 , g^2 , and g^3 ; the solvent dissolves the soluble constituents of the raw material and falls through the sieve bottoms c^1 , c^2 , and c^3 into the collectors or troughs f^1 , f^2 , and f^3 . The solvent collected in the trough f^3 will only contain small quantities of substance

dissolved out from the raw material because the raw material has already been lixiviated to a considerable extent in the containers b^1 and b^2 . Through the pipe conduit g^2 this solvent is conveyed to the raw material in the container b^2 , passes through this after taking up a part of the material to be dissolved out into the trough f^2 from here through the pipe conduits g^1 to the raw material in the container b^1 , which still contains all the parts which are to be dissolved out, and then into the trough f^1 , from which now highly enriched it is conveyed through the pipe conduit g^1 for known further treatment.

Having now particularly described and ascertained the nature of this invention and in what manner the same is to be performed, I declare that what I claim is:

An apparatus for lixiviating solid materials with liquid solvents, comprising a closed chamber, a series of annular containers coaxially mounted one above the other within the chamber, each container consisting of a solid revoluble side wall and a perforated bottom secured thereto, a stationary wall with an opening forming the opposite side of each container, a scraper on the stationary wall adjacent said opening and extending across the said bottom, conveying the material from the annular course through the opening into the next lower container, and annular trough beneath each of said containers, conduits leading from a lower trough to an upper container with trough and pumps conveying the solvents through said conduits, a supply conduit for the solvent from a source to the lowermost container, a delivery conduit for the solvent from the uppermost trough out of the apparatus, a filling hopper for raw material at the top of the chamber and an outlet opening at the bottom thereof for lixiviated material.
